UNITED STATES PATENT OFFICE.

WILEY CRAIG, OF CINCINNATI, OHIO.

DRAFT REGULATOR.

Application filed September 5, 1919. Serial No. 321,946.

To all whom it may concern:

Be it known that I, WILEY CRAIG, a citizen of the United States, and a resident of Cincinnati, in the county of Hamilton and State of Ohio, have invented certain new and useful Improvements in Draft Regulators, of which the following is a full, clear, and exact description, reference being had to the accompanying drawings, forming part 10 of this specification.

My invention relates to devices for automatically regulating damper position by means of a motor that is itself controlled by the pressure of air over the grate of the 15 furnace, or other chamber that is damper-controlled. My object is to obtain a substantially uniform pressure in furnaces and other damper-controlled devices, in an automatic manner.

20 In the devices of the past, it has been the practice to hinge plates either horizontally or vertically in an opening in the side of a furnace, and by said plates control the damper operating motor. It has also been 25 for many years the practice to control the damper motor by means of a pneumatic diaphragm, or the like.

In all such devices, there is expensive 30 construction and more or less delicate mechanism, and it is the object of my invention to provide a stout and inexpensive device, which is very compact and is readily adjusted. In this connection I employ as a 35 controlling member an inverted float, which is suspended on the valve rod that controls the water motor, so that the valve works on the axis of the float. The water motor is mounted on the top of the float tank, without loss of space, and some of the water 40 flowing through the valve ports runs into the tank and maintains the fluid level therein.

The motor is of special construction and positive and accurate in its operation, being calculated to adjust the damper to the position desired without undue oscillation, and by a simple operation.

Other advantages of my device will be noted hereinafter, and I accomplish my objects by that certain construction and arrangement of parts to be hereinafter more specifically pointed out and claimed.

In the drawings,

Figure 1 is a central vertical section taken through the device.

55 Figure 2 is a top plan view thereof.

The device is shown as controlling a dam-

per 1 set in a stack 2. On the shaft of the damper is a bell crank 3, one end of which is counterbalanced by a weight 4, and the other connected to a cable 5.

60 The motor comprises a casing or cylinder 6, in which slides a piston 7. This piston is surrounded by a cup leather 8, and together with the piston and the cup leather on the end of the piston rod 9, is the follower 65 head 10.

The piston rod passes through a stuffing box 11 on the upper end of the motor and is connected to the cable 5, so that the position of the piston rod controls the position 70 of the damper, acting as it does against the counter-weight 4.

75 The piston in the cylinder is maintained under constant pressure during the normal operation of the device by hydrant pressure or otherwise, and the cylinder for this purpose is provided with an inlet port 12 for the supply pipe 13, the supply pipe being provided with a stop cock for closing off the water when desired, although it will be 80 understood that in normal operation the valve is open. One side of the cylinder is provided with a valve chamber 18 in the wall of the cylinder, and there are a series of small ports 19, one above the other, from 85 the cylinder into this valve chamber. The valve chamber is also provided with an outlet port 17 at the bottom.

86 The piston valve 19 snugly fits the piston valve chamber and its position controls the 90 port 19 which is open to flow of water through the cylinder.

95 Thus upon operation of the piston valve, the point subjected to water pressure against the piston is definitely located as at the under edge of the upper exposed port 19, and since the counterweight on the damper lever tends to pull up the piston itself, it will rise as far as it is permitted against the pressure of the stream of water maintained through the motor. The flow of water is not excessive, as but one port is open at a time, and very little force is necessary to lift the piston.

100 A large degree of accuracy is obtained with this device in a very simple manner. The piston valve is connected by a cable 20, which passes over a sheave 21, with a weight hook 22. By varying the weights 105 applied to the weight hook, the tendency 110 of the piston valve to rise out of the piston valve chamber can be controlled, and thus

the height thereof, at a given suction applied to the inverted bell, which will now be described.

A tank 24 is provided, which has suitable flanges 25 for securing it to the wall of a furnace or the like, and has a head 26, on which the water cylinder above described is mounted. This head is preferably provided with a flange 26^a, forming a pan to receive the overflow from the water which is discharged from the pan through the pipe 26^b.

Within the tank is a suction or pressure tube 27, which extends up through the bottom thereof to a point above the overflow port 28, in the wall of the tank.

The piston valve has a stem 29 which extends down through the head of the tank, preferably fitting the opening in the base of its chamber, and the head of the tank loosely, so that a sufficient amount of water will run through to maintain the fluid level in the tank.

An inverted bell or hood 30 is provided, which is adjustably secured to the valve stem by means of interior and exterior nuts 31 threaded on the stem. Around the base of the hood is formed an air chamber or float chamber, which tends to react against the tendency of the hood to sink beneath the surface of the fluid in the tank, during periods of excessive suction. The air space between the hood and the water level is in communication with the suction tube 27, so that the suction in this tube will control the position of the float, causing the float to fall as the suction increases and to rise as the suction decreases except as counteracted by the amount of air beneath the float, the buoyancy chamber 27^a around the base of the float and the counterweights on the weight hook 22.

The head of the tank is left open to permit atmospheric pressure to control on the exposed portion of the float, there being preferably a wide opening 32 for this purpose in the head of the tank.

The purpose of the buoyancy chamber at the base of the float is in order to leave for the counterweights 23 the regulation of the device, and by the addition of weights the damper position can be controlled; another adjustment of this nature but more permanent, and less readily changed will be that of the nuts 31.

It may be readily observed that the piston valve and stem are axial with the axis of the inverted hood or float, and there are no hinges or other power transmitting devices except in one vertical line from the float to the motor control so that the valve 19^a rises and falls to open or close the ports 19 to exactly the same extent and simultaneously with the movement of the float, without any friction of any hinged or pivoted parts. I am thus able to furnish an

effective apparatus in much smaller compass than is possible with the same extent of valve movement in any other construction.

The construction of the motor itself insures against fluttering of the damper, as the motions of the piston of the motor will be rapid and accurate, but "dead beat" in a very large degree.

The whole device need not be large, and requires no special furnace construction, and is fully effective to control a furnace damper or the like, by means of suction applied from the desired source through the suction tube. This tube will be connected to the combustion chamber of a furnace, or the chamber of any damper-controlled device which it is desired to regulate. The degree of damper angle is readily controllable by the mere addition of counterweights. 35

In the above matter I have referred to merely one embodiment of my invention, and I do not wish to be understood by this to mean that this is the only way, and the mechanical expedients the only ones by which my invention can be accomplished. On the contrary, it is my desire that my claims which follow be construed with the full application of the doctrine of equivalents. As an example of the benefits and 95 advantages due to the fact that the motor-control valve is positioned and adapted to be moved axially of the float, I might say that for ordinary furnace regulation I am able to construct the regulator within a 100 height of twenty-eight inches and width and breadth of sixteen inches.

Having thus described my invention, what I claim as new and desire to secure by Letters Patent, is:—

1. A damper regulator comprising a suspended float controlled by pressure in a chamber to be influenced by the damper, a damper motor adapted when actuated to move the damper, said motor comprising a piston under constant control of a column of water, with means on the float adapted to control the said column. 110

2. A damper regulator comprising a suspended float controlled by pressure in a chamber to be influenced by the damper, a damper motor adapted when actuated to move the damper, and means on the float to control the motor, said means being positioned and adapted to move axially of the 115 float as distinguished from a pivotal element on a hinged float.

3. A damper regulator comprising a tank, a pressure-controlled motor on the tank, a float in the tank under influence of the damper-controlled draft, and a rectilinear device mounted on the float, adapted to move through a longitudinal path, for controlling the pressure on the motor. 125

4. A damper regulator comprising a tank, 130

5 a pressure-controlled motor, an inverted vessel float, a reciprocating device on the float for controlling the pressure on the motor, and means for balancing the reciprocating device, said reciprocating device being axial of the float.

10 5. A damper regulator comprising a damper, a vertically and rectilinearly moving member, the position of which is controlled by the draft influenced by said damper, a pressure-controlled motor and connection therefor with the damper, and a rectilinear reciprocating device on the vertically movable member adapted to control the motor.

15 6. A damper regulator comprising a damper, a vertically moving member, the position of which is controlled by the draft influenced by said damper, a pressure-controlled motor, said motor having a piston, connection therefor to the damper, and a reciprocating device in axial alignment with and controlled by the vertically moving member, said reciprocating device adapted to control the pressure in the motor to locate the piston at a position corresponding to the position of the reciprocating device.

20 7. A damper regulator comprising a damper, a vertically moving member, the position of which is controlled by the draft influenced by said damper, a pressure-controlled motor, said motor having a piston, connection therefor to the damper, and a reciprocating device in axial alignment with and controlled by the vertically moving member, said reciprocating device adapted to control the pressure in the motor to locate the piston at a position corresponding to the position of the reciprocating device, and means for balancing the reciprocating device.

25 8. A damper regulator comprising in part a motor having a piston, an inverted vessel float influenced by the dampered draft, a reciprocating valve in the motor for controlling the position of the piston therein to cause it to be located at positions corresponding to positions of the valve, said float being suspended from said valve and in axial alignment therewith.

30 9. A damper regulator comprising in part a motor having a piston, an inverted vessel float influenced by the dampered draft, a reciprocating valve in the motor for controlling the position of the piston therein to cause it to be located at positions corresponding to positions of the valve, said float being suspended from said valve, and a cord from said valve, said cord being under the control of a weight hook for receiving regulating weight.

35 10. The combination of a reciprocating draft-controlled balanced valve, of a motor having a water inlet to admit a constant flow of water, a piston in the motor, and a longi-

tudinally extending water-controlling port element in the motor adapted to be closed 65 and opened progressively by the valve to control the length of the water column in the motor above the piston, and means for holding the piston up against the column of water.

40 11. A pressure-controlled motor for use with a reciprocating draft-controlled member, comprising a cylinder, a water inlet port therefor, a chamber in the cylinder wall having an outlet, the cylinder wall having 75 a series of holes into the chamber or their equivalent, said reciprocating member adapted to move in said chamber free from pressure and to close the holes therein, for the purpose described.

45 12. A damper-controlling piston under the influence of a constant flow of water, a cylinder in which said piston is adapted to move, a series of outlets in different longitudinal positions in the motor or their equivalent, and a draft-controlled balanced valve for closing the outlets dependent upon its position, for the purpose described.

50 13. A damper regulator comprising a tank, a water motor on the tank with a constant flow of water therefrom, a draft-controlled float in the tank, a motor-controlling element under the influence of the float, and means for automatically supplying the tank with water discharged from the motor.

55 14. A damper regulator comprising a damper connection, a piston under constant pressure of a flow of motive fluid, a draft controlled reciprocating member and a balanced connection from the reciprocating member adapted to control the point of escape of the motive fluid from exertion of pressure against the piston.

60 15. A damper regulator comprising a damper, an actuating member under constant pressure, and balanced connection therefor with the damper, a balanced member under control of the pressure in the damper-controlled chamber and connection therefor with the actuating member whereby the movement of the balanced member will vary the pressure on the actuating member to shift the damper.

65 16. A damper regulator comprising a damper, an actuating member under constant pressure, with balanced connection therefor with the damper, means for changing the balance, comprising a second balanced member under control of the pressure in the damper-controlled chamber, and a direct axial connection intermediate the actuating member and the second balanced member whereby variations of pressure influenced by the damper will vary the position of the actuating member to open or close the damper.
